DESCRIPTION

FIG. 1 is a perspective view thereof.

FIG. 2 is a front view thereof;

FIG. 3 is a rear view thereof;

FIG. 4 is a left side view;

FIG. 5 is a right side view;

FIG. 6 is a top plan view; and,

FIG. 7 is a bottom view of the invention.

The broken line showing of the rake handle is included for the purpose of illustrating environmental structure and forms no part of the claimed design.
